(57) **CLAIM**

The ornamental design for a combined tripod and reflector for photography, as shown and described.

DESCRIPTION

FIG. 1 is a perspective view of a combined tripod and reflector for photography showing our new design;

FIG. 2 is another perspective view thereof;

FIG. 3 is a folded view with the reflector shown separated;

FIG. 4 is a front view of the reflector shown separate for ease of illustration;

FIG. 5 is a front view of the combined tripod and reflector;

FIG. 6 is a back view thereof;

FIG. 7 is a left view thereof;

FIG. 8 is a right view thereof;

FIG. 9 is a top view thereof;

FIG. 10 is a bottom view thereof;

FIG. 11 is a partially enlarged view of portion 11 shown in FIG. 1;

FIG. 12 is another partially enlarged view of portion 12 shown in FIG. 1;

FIG. 13 is a third partially enlarged view of portion 13 shown in FIG. 1;

FIG. 14 is a partially enlarged view of portion 14 shown in FIG. 3; and,

FIG. 15 is a partially enlarged view of portion 15 shown in FIG. 2.

The broken lines shown in the drawings depict portions of the combined tripod and reflector for photography, the dash-dot-dash broken lines demarcate the enlarged views; all broken lines form no part of the claimed design.
